CONVERSION OF HYDROCARBON OILS

Le Roy G. Story, Mount Vernon, N. Y., assignor
to The Texas Company, New York, N. Y., a cor-
poration of Delaware

Application April 21, 1931, Serial No. 531,693

7 Claims. (Cl. 196—60)

This invention relates to the conversion of hydrocarbon oils and has to do particularly with a combination of liquid phase and vapor phase cracking which provides certain advantages and presents features of novelty that will be more fully described and claimed hereinafter.

An important object of the present invention is to produce from a fresh charging stock, essentially, a residue of coke, a distillate of gasoline having a high antiknock value and fixed gases which may be used as fuel or for other purposes as desired.

The invention contemplates the stripping of fresh charging stock by contact with the vapors from a coking operation, the separation of a clean cracking stock for a pressure cracking system, the separation of selected cuts for vapor phase cracking and the coking of the residue liquids from the stripping and pressure cracking operation by the sensible heat of the vapor phase cracked products. With suitable type of apparatus and novel methods of operation the volatile products may be concentrated at one zone in the system whereby a gasoline of high antiknock value, consisting of both liquid phase and vapor phase cracked products, may be separated, the heavier components fractionated to produce selected cuts which may be subjected separately to a pressure cracking system and a vapor phase cracking system, while the unvaporized residual oil from the system may be reduced to coke in coking stills.

The process of the invention is flexible so that a wide selection of cuts for cracking may be made by segregating various fractions according to the desired volatility or refractoriness and each fraction subjected to the most suitable type of conversion operation. Accordingly, the low boiling products vaporized in the pressure cracking operation may be separately dephlegmated to produce selected cuts for vapor phase and liquid phase cracking; the residual liquid or pressure tar may be flash distilled under reduced pressure to likewise produce selected cuts for the same purpose, if desired; or, the entire vapor fraction from both the pressure stills and the flash still may be concentrated in one large tower, which also receives vapors from the crude stripper, and the resulting mixture of vapors fractionated to separate the desired gasoline, and to produce at the same time a fraction suitable for vapor phase cracking stock and a clean condensate adapted for pressure still cracking.

The invention may be more clearly understood by referring to the accompanying drawing where-

in an apparatus is shown for conveniently carrying out the invention and forming one embodiment thereof.

In the drawing the reference character 1 represents a heater for heating oil under pressure; 2 and 3 a pair of stills for separating vapors from residual oil; 4 a dephlegmator for dephlegmating or fractionating vapors from the stills 2, 3; 5 a vapor phase cracker for cracking oil in the vapor phase; 6 and 7 a flash still and dephlegmator for vaporizing residue and fractionating the vapors from the stills, 2, 3; 8 and 8a, coke stills for reducing residual oil to coke by the heat of the cracked products from the vapor phase cracker 5; and 9 a combined stripper and fractionating tower for stripping crude and for fractionating any or all the vapors from the stills 2, 3, flash still 6, vapor phase cracker 5, and coke stills 8 and 8a.

The heater 1 comprises any well known type of furnace having a coil or tubular heater 10, located therein, and connected to an extraneous supply line 11 and a clean distillate charge line 12. A burner 13 supplies heat to raise the oil passing through the coil 10 to conversion temperatures. A transfer line 14, conducts oil from the heater to either or both of the stills 2 and 3 by means of the branches 15 and 16 respectively.

The stills 2 and 3 are shown as vertical chambers having a vapor connecting line 20 and a liquid overflow pipe 21. The vertical type of still is shown for illustrative purposes only and other shape and designs of stills may be employed, if desired, with equal success. The stills are preferably insulated to retain the heat content of the oil and provide reaction time at conversion temperatures. Each still is provided with residue draw-off lines 23 and 24 for withdrawing residual liquid continuously or intermittently. A vapor pipe 25, regulated by a valve 26, conducts vapors from the stills 2 and 3 to a line 27, referred to hereinafter. A branch line 28, in which is interposed a valve 29, serves to conduct the vapors, if desired, to the dephlegmator 4.

The dephlegmator 4 may conveniently take the form of a bubble tower equipped with trays to contact the vapors and reflux condensate. A cooling coil 30 is provided in the top of the dephlegmator to supply cooling thereto by an extraneous cooling medium. A vapor pipe 31 conducts vapors from the dephlegmator to a condenser coil 32. A condensate line 33 serves to convey the condensate from the condenser to a receiver 34 which is equipped with the usual gas release line 35 and liquid draw-off pipe 36.

The dephlegmator is further provided with lines 36' and 37, regulated by valves 38 and 39 respectively, communicating with the bottom thereof to withdraw reflux condensate from the 5 bottom of the tower. A line 40, in which is interposed a valve 41, connected to the side of the dephlegmator, serves to withdraw a side cut therefrom, if desired. The reflux condensate pipes 36 and 37, as well as the side pipe 40, separately connect to a line 27, referred to heretofore, which communicates at different elevations with the upper fractionating section of the tower 9 by means of branch lines 42 and 43. A line 45, regulated by valve 46, communicating with the line 27, leads to the tubes or coil 47 located in the vapor phase cracking furnace 5.

The vapor phase cracker 5, shown for purposes of illustration as a diagrammatical section, may be any well known or preferred type of vapor phase cracking apparatus. A convenient type of furnace for such use may be similar to that disclosed in U. S. Patent No. 1,717,334, June 11, 1929, to Luiz de Florez. A pipe 48, controlled by valves 49 and 50, connects the cracking coil 47 20 to the stripper section of the tower 9. Branch lines 51 and 52 connect the line 48 to the coke stills 8 and 8a. A vapor line 53 serves to conduct vapors from the coking stills 8 and 8a to the bottom of the stripper section of tower 9.

Referring now to the flash still 6, a residue line 55 serves to conduct residuum thereto from the stills 2 and 3. A vapor line 56 conducts vapors from the flash drum 6 to the dephlegmator 7. A vapor line 58 connects the dephlegmator 7 to the line 27 referred to heretofore. A residue draw-off line 60 serves to withdraw residue from the flash still 6. A branch line 61 serves to conduct the residue, if desired, to a charge line 62 leading to the stripper section of tower 9. A reflux condensate line 63 conducts reflux condensate from the bottom of dephlegmator 7 to the clean distillate charge line 64. A branch line 65, controlled by valves 66 and 67, connects the reflux line 63 with the line 27, whereby the condensate may be transferred to the fractionator 9. A branch line 68, controlled by valve 69, connects the line 65 to the line 27 ahead of valves 70 and 71 in line 27 so that the condensate, if desired, may be sent to the vapor phase cracker via lines 27 and 45. A condensate line 75 serves to withdraw condensate from the middle of dephlegmator 7 to the line 65.

Referring to the stripper and fractionator 9, it will be noted that the upper section of the tower 55 constitutes a fractionating tower while the lower section constitutes the stripper. The sections are separated by a partition 80 having a vapor riser 81 therein so that vapors from the stripper may pass to the fractionator. While the stripper and fractionator are shown as a single tower with the fractionator superimposed on the stripper, nevertheless the two sections may be made as separate units and the invention contemplates such an arrangement.

A charge line 62 leads to the top of the stripper to conduct fresh charge thereto as well as residuum from the line 61, if desired. A residue draw-off line 83 serves to withdraw unvaporized oil from the bottom of the stripper. A branch line 74, having a pump 84' serves to transfer the residuum from line 83, if desired, to the line 48 to be mixed with the cracked products from the vapor phase cracker 5 and thence to be conducted to the coke stills or to the stripper. A branch line 75, controlled by valve 86, connects the lines

61 and 84 whereby the residuum from the flash still 6 may be contacted with the products from the vapor phase cracker.

A clean distillate or reflux condensate line 90, connected to line 43, serves to withdraw condensate collecting in the bottom of the fractionator 9 or condensate in line 27 to storage or to conduct the condensates to the charge line 64 whence they are forced by pump 91 to the coil 10. A condensate line 93, connected to the side of the fractionator and having a pump 93', serves to conduct, if desired, a side cut from the fractionator to the line 45 leading to the vapor phase cracker 5. A vapor line 95 conducts vapors from the top of the fractionator to the condenser coil 96. A condensate line 97 connects the condenser coil 96 to a receiver 98 which is equipped with the usual gas release line 99 and liquid draw-off line 100.

In practicing the invention with an apparatus such as that shown in the drawings, charging 20 stock, such as crude oil, is charged to the stripper through line 62 wherein the fresh charge comes in contact with the hot vapors therein and the charge may be partially cracked and the lighter constituents vaporized. The vapors, including 25 the volatilized constituents of the fresh charge, pass through the riser 81 to the fractionator. A clean distillate collects above the partition 80 and is conducted by the lines 90 and 64 to the pressure cracking coil 10. The clean distillate 30 passing to the coil 10 is preferably a cracking stock of the nature of gas oil. If desired, an extraneous charge of oil may be introduced through the line 11. The addition of extraneous oil is sometimes desirable in order to provide a uniform 35 charging rate in case the supply from the fractionator runs low and more particularly is such a supply of charge from line 11 convenient in starting up operations.

The oil in the heating coil 10 is raised to conversion temperatures of the order of 750° F.—950° F. and a pressure of 200-600 pounds per square inch may be carried on the coil and stills 2 and 3. Two stills are shown in the drawings but any number may be used. Likewise, the stills 45 are shown connected with vapor lines and liquid overflow lines, but it is contemplated that a low liquid level may be maintained in the stills in which case there would be no overflow but instead the hot oil may be charged to one or both stills 50 and the entire contents of the stills maintained substantially as vapors. The vapors from the stills 2 and 3 pass through the line 25 and may be passed directly to the fractionator 9 through line 27.

In one method of operation the vapors from stills 2 and 3 may be passed through line 28 to the dephlegmator 4. In the dephlegmator the vapors are fractionated to separate a gasoline fraction which is condensed in condenser 32 while the 60 heavier constituents are collected as reflux condensate. The reflux condensate may be collected entirely in the bottom of the tower 4 or separated into selected cuts and one cut taken off as a side stream through line 40. In case a side stream 65 is taken off it is preferable to charge this cut to the vapor phase cracker through line 45 while the heavier cut in the bottom of the tower 4 is passed through line 36 and line 27 to the fractionator 9 or directly to line 90 to be backtrapped 70 to the heater coil 10. When no side cut is taken from the tower 4 then the reflux may be passed entirely or in part through lines 37 and 45 to either the vapor phase cracker 5 or the tower 9.

The residue from stills 2 and 3 may be con- 75

ducted continuously or intermittently to the flash still 6. A reduced superatmospheric pressure is maintained in the still 6 so that the lighter fractions of the residual oil are immediately flashed by their sensible heat into vapors. The vapors pass to dephlegmator 7 while residue is withdrawn through line 60 to be disposed of as described hereinafter. The vapors in dephlegmator 7 may be separated into one or more cuts, as desired. In some cases it may be desirable to pass a substantial amount of the vapors to vapor phase cracker 5 and this may be done by suitable regulation of valves 70 and 71 in line 27, or the vapors by other regulation of the same valves may be sent directly to the fractionator 9. Likewise, one or two cuts of condensate may be made in the tower 7, these cuts being drawn off through lines 63 and 75. In this way a side cut may be taken off through line 75 and sent to the vapor phase cracker by suitable regulation of valve 69 in branch line 68 and valve 67 in line 66, while a heavier condensate from the bottom of tower 7 may be returned to coil 10 through line 64. In some cases it may be desirable to make a single cut of condensate in tower 7 and this cut may be withdrawn through line 63 and passed to the coil 10 or conducted through line 65 to either the vapor phase cracking coil or to the fractionator 9 by suitable regulation of valves 69 and 67 in lines 68 and 66 respectively.

While I have described the manner in which particular fractions from either the dephlegmator 4 or dephlegmator 7 may be passed to the vapor phase cracker 5 or the fractionator 9, it is to be understood that selected fractions of liquids and/or vapors from both dephlegmators may be passed simultaneously to the vapor cracker 5 or fractionator 9. It will be observed therefore that flexibility of operation is an essential feature of my invention whereby selected cuts may be treated in a manner to provide optimum conditions for both yield and quality of the desired finished products.

The oil in passing through vapor phase cracker 5 is raised to a temperature suitable for conversion in the vapor phase, say between 950° F. and 1150° F. The hot products of conversion may be transferred through line 48 directly to the stripper section of the tower 9. It is preferable, however, that these products go to the coke stills 8 and 8a by means of lines 51 and 52, in order that the heat thereof may be used for coking the residual oils from the system. Two coke stills are shown, for purposes of illustration, but only one is ordinarily used at a time while the other is cleaned of the coke deposition therein. The vapors from the coke stills pass through lines 53 to the stripper section where they contact the heavy oil charged thereto through line 62.

The residual oil from the system is preferably commingled with the hot vapors from the vapor phase cracking operation. Referring first to the residuum from the flash still, this oil may be passed through lines 61 and 62 to the stripper. It is preferable, however, to by-pass it through lines 85 and 84 to be commingled with the vapor phase cracked products. Therefore, this residue may be used to cool the cracked products in case they are passed directly to the stripper through line 48 or the mixture of residuum and vapors may be passed through lines 51 and 52 to the coke stills where the residue is reduced to coke by the sensible heat of the vapors. Likewise, the unvaporized oil collecting in the bottom of the stripper is withdrawn through line 83 and passed

entirely or in part, alone or in mixture with the residuum from flash still 6, into the line 48 to be treated as just described.

The vapors collecting in the fractionator section of tower 9, which may comprise all or a part of the vapors from the entire system, depending on whether the dephlegmator 4 is by-passed, are fractionated and the reflux condensate or clean distillate, entirely or in part, passed to the heater coil 10. Sometimes it is desirable to separate the reflux condensate into selected cuts, and therefore, I have shown a line 93 for making a side cut to be returned to the vapor phase cracker 5. The latter is particularly advantageous in case the dephlegmator 4 is by-passed and all the vapors concentrated in the fractionator section of tower 9.

Obviously many modifications and variations of the invention, as hereinbefore set forth, may be made without departing from the spirit and scope thereof, and therefore only such limitations should be imposed as are indicated in the appended claims.

I claim:

1. The method for conversion of hydrocarbon oils which comprises passing fresh charging stock into contact with vapors from a coking zone to form unvaporized liquid and vapors, fractionating said vapors to form a vapor fraction and a reflux condensate, subjecting said condensate to conversion conditions of temperature and superatmospheric pressure to separate low boiling products as vapors from residual oil, flash distilling said residual oil to produce an unvaporized residual liquid and a selected distillate for vapor phase cracking, subjecting only said selected distillate to a vapor phase cracking operation, mixing the unvaporized residual oil from the system with the products from the vapor phase cracking operation and passing the resulting mixture to said coking zone.

2. The method for the conversion of hydrocarbon oils by a series of continuous steps which comprises subjecting a hydrocarbon oil to conversion conditions of temperature and superatmospheric pressure to produce a vapor fraction and an unvaporized residue, fractionating said vapor fraction in a first fractionating zone to form a desired product, subjecting the unvaporized residue to flash distillation in a flashing zone under a reduced superatmospheric pressure, fractionating the vapors evolved during flash distillation in a second fractionating zone to separate a selected fraction suitable for vapor phase cracking, subjecting said fraction, while still retaining heat from its previous treatment, to a vapor phase cracking operation, conducting the vapor phase cracked products to a coking zone, separate from said flashing zone, passing the vapors from the coking zone to a stripping zone, introducing fresh charging stock into said stripping zone, separate from said flashing zone, separating a clean condensate from the resulting vapors, utilizing clean condensate so obtained, as said hydrocarbon oil undergoing conversion, and passing residual oil from the stripping zone to said coking zone.

3. The process of treating hydrocarbon oil which comprises introducing crude oil into a stripping zone, wherein heat is supplied by hot vapors and the crude is partially vaporized, collecting a clean, relatively heavy condensate, and an intermediate condensate, and condensing the lightest of the crude vapors as a desired product, introducing said relatively heavy condensate into

a cracking zone wherein cracking conditions of temperature and pressure are maintained and said condensate is subjected to conversion, separating the products of conversion into vapors and a liquid residue, extracting gasoline from said vapors, introducing said residue into a flashing zone of reduced pressure wherein partial vaporization thereof takes place, subjecting resulting vapors to partial condensation to form a relatively heavy residue, extracting gasoline from said vapors, introducing the residue from said flash zone into a coking zone, cracking in the vapor phase the intermediate condensate last mentioned, introducing the highly heated cracked vapors into said coking zone to maintain the temperature thereof, and introducing vapors from said coking zone into said crude stripping zone to aid in the stripping of said crude oil.

4. The process of treating hydrocarbon oil which comprises introducing crude oil into a stripping zone wherein heat is supplied by hot vapors, and the crude is partially vaporized, collecting a clean relatively heavy condensate and condensing the lightest of the crude vapors as a desired product, introducing said condensate into a cracking zone wherein cracking conditions of temperature and pressure exist and said condensate is subject to conversion, separating the products of conversion into vapors and a liquid residue, extracting gasoline from said vapors, introducing said residue into a flashing zone of reduced pressure wherein partial vaporization thereof takes place, subjecting resulting vapors to partial condensation to form a condensate, leaving relatively light vapors uncondensed, introducing the residue from said flashing zone into a coking zone, cracking in the vapor phase the condensate last mentioned, introducing the highly

heated cracked vapors into said coking zone to maintain the temperature thereof, and introducing hot vapors from said coking zone into said stripping zone to aid in the stripping thereof.

5. A process in accordance with claim 3 wherein in said relatively heavy condensate second mentioned is recycled to said cracking zone first mentioned.

6. A process in accordance with claim 3 wherein unvaporized portions of said crude charging oil are introduced into said coking zone.

7. The method for the conversion of hydrocarbon oils by a series of continuous steps, which comprises subjecting a hydrocarbon oil to conversion conditions of temperature and superatmospheric pressure to produce a vapor fraction and an unvaporized residue, fractionating said vapor fraction, in a first fractionating zone, subjecting the unvaporized residue to flash distillation in a flashing zone under a reduced superatmospheric pressure in a flashing zone, separate and apart from the coking zone hereinafter specified and from the resultant vapors produced in the coking operation, fractionating the vapors evolved during flash distillation, in a second fractionating zone, to separate a selected fraction suitable for vapor phase cracking, subjecting said fraction, while still retaining heat from its previous treatment, to a vapor phase cracking operation, conducting the vapor phase cracked products to a coking zone separate from said flashing zone, passing the vapors from the coking zone to a stripping zone, introducing fresh charging stock into said stripping zone and passing residual oil from the stripping zone to said coking zone.

LE ROY G. STORY.
